JAMES L. SHORT, OF GOSPORT, IOWA.

Letters Patent No. 68,535, dated September 3, 1867.

IMPROVED TRACE-FASTENER.

The Schedule referred to in these Letters Patent and making part of the same.

TO ALL WHOM IT MAY CONCERN:

Be it known that I, JAMES L. SHORT, of Gosport, in the county of Marion, and State of Iowa, have invented a new and useful improvement in Trace-Fastenings; and I do hereby declare that the following is a full, clear, and exact description thereof, which will enable others skilled in the art to make and use the same, reference being had to the accompanying drawings, forming part of this specification.

This invention relates to an improvement in trace-fastenings, and consists of a catch swung in a metal box, and held down by means of a spring. The trace may be released from the catch by the driver pulling on a cord, when the horse would be immediately detached from the carriage. In the accompanying drawings—

Figure 1 is a side view of my improved trace-fastener, and

Figure 2 a horizontal section thereof, at line *xx*.

Similar letters of reference indicate corresponding parts.

A A is a metal box, attached to the shaft or single-tree; B, a catch swung in the box A, on the pivot *a*, and held down by the spring C. E is the trace-tug, catching on B, the trace being attached at *e*. D is a guard, through which passes the rope *d*, attached on the outside of the catch B, and placed within reach of the driver. The trace-tug is slipped over the catch B, by which it is firmly held. To release it the handle *b* of the catch B may be pressed down, when the tug will fall out, or the driver may pull on the rope *d*, effecting the same object, and detaching the horse from the carriage in an instant.

Having thus described my invention, what I claim as new, and desire to secure by Letters Patent, is—

1. The metal box A, attached to the shaft or single-tree, substantially as described.
2. The catch B, held down by the spring C, combined with the trace-tug E, or their respective equivalents, substantially as and for the purposes described.
3. The single-tree attachment, formed of the box A, catch B, and spring C, or their respective equivalents, substantially as described.
4. The combination with the above-described single-tree attachment of the guard D, or its equivalents, substantially as described.
5. The employment of the safety-cord *d*, with the single-tree attached, with or without the guard D, substantially as herein specified and described.

JAMES L. SHORT.
